UNITED STATES PATENT OFFICE.

SAMUEL P. SPOONER, OF BUCKLIN, ASSIGNOR OF FIFTY-ONE SEVENTY-
SECONDS TO DANIEL B. HOLMES, ROBERT H. DRENNON, WM. C. DUVALL,
AND EMIL WERK, ALL OF KANSAS CITY, MISSOURI.

METALLURGIC FURNACE.

SPECIFICATION forming part of Letters Patent No. 274,403, dated March 20, 1883.

Application filed October 2, 1882. (No model.)

To all whom it may concern:

Be it known that I, SAMUEL P. SPOONER, of Bucklin, in the county of Linn and State of Missouri, have invented a certain new and useful Metallurgic Furnace; and I hereby declare the following to be a full, clear, and exact description thereof, reference being had to the accompanying drawings, making part of this specification, in which—

10 Figure 1 is a side elevation of the furnace and connections. Fig. 2 is a vertical cross-sectional view of the furnace and portions of the connections. Fig. 3 is an elevation with force-pumps and condensers removed. Fig. 4 is a horizontal cross-sectional view on the line xx of Fig. 2. Fig. 5 is a plan of the bottom of the furnace. Fig. 6 is a view of the central partition removed.

15 The object of my invention is to provide a furnace for metallurgic purposes wherein the draft shall be direct from its point of entrance to the point of exit; the draft shall be in a series of jets given substantially a direction parallel to the longitudinal axis of the body of the furnace; the operations of smelting and refining can be carried on conjointly or separately, and wherein the condensation of the fumes and gases is greatly facilitated; and to this end the invention consists in novel features of construction and combination of parts, all as will be hereinafter fully described, and set forth in the claims hereto annexed.

In order that those skilled in the art may make and use my invention, I will proceed to describe the manner in which I have carried it out.

In the said drawings, A is the body of the furnace, which is lined with fire-brick sustained by a series of shelves, $a a$; and B is a central flue at the top, for the exit of the products of combustion.

Dividing the body A on a central vertical line is a hollow partition or diaphragm, C, contracted at its center and widening at the edges, as seen in Fig. 4. A continuous water-circulation is kept up in this hollow partition by means of water-pipes $b b'$, projecting through the bottom of the furnace. Doors D D are pro-

vided on both sides of the furnace for charging the furnace, so that access may be had on 50 each side of the diaphragm or partition C. Openings through the walls of the furnace and spouts $d d'$ at varying heights are provided for drawing off the slag or the molten metal at various elevations. The bottom of the furnace, 55 shown in this instance to be conical, though it need not be so shaped, is hinged to the body of the furnace at $e e$ by means of a pin or bolt, e' , whereby the bottom may be opened or entirely removed at will.

On the inner surface of the bottom are concentric air-pipes E, provided with a series of perforations, $f f'$, and connecting exteriorly with a blast-pipe, F, communicating with a fan-blower or other desirable means for forcing 65 air. When closed the bottom of the furnace is secured by a latch or catch, g.

The central flue, B, passes into a cross-flue, G, and above it, where it terminates in the dome G' , provided with a cover, h, which may 70 be removed when firing up the furnace, but which normally tightly covers said dome. One end of cross-flue G is provided with an inwardly-opening valve, i, controlled by a spring, i' , which opens and relieves the flues should 75 the exhaust-pump create too great a vacuum.

In the end of cross-flue G opposite to the valve i are inserted pipes H H, leading to air or exhaust pumps I I, which are near the condensing-chambers K K. Between the ends of 80 pipes H H and the flue B a water-pipe, L, enters cross-flue G and terminates in a rose or spraying device, l. (See Fig. 2.) Water under pressure is conveyed through pipe L, and while the furnace is in operation a spray of water is 85 continuously thrown in flue G across the line of travel of the products of combustion. The pipes H conduct the fumes and gases to exhaust-pumps I, which, with the well-understood arrangement of valves, forces said fumes 90 and gases, with a positive high velocity, through pipes N into the water in the condensing-tanks K K.

If found desirable, the upper side of cross-flue G may be tapped at n, and a pipe, M, introduced to carry the most volatile or lightest

2
gases, which are next to the upper surface of the flue, back into the furnace to aid combustion.

It is obvious that the furnace on one side of the partition may alone be charged with ore of the precious metal, fuel, and flux for smelting, and that as the smelting goes on the molten metal will flow below the partition, through the opening between the partition and the bottom of the furnace, into that half of the furnace having no charge of ore in it. The jets of air or other oxidizing medium, passing up through the molten metal on the side without the charge of ore, oxidizes or burns out all impurities and base metals. Thus it will be seen that the operations of smelting and refining are carried on in the same furnace, the purer bullion being drawn from the opening and spout *d* or *d'* from time to time.

20 A positive heavy pressure is highly desirable to force the fumes and gases into the condensers *K K*, and this can best be attained by a force-pump, *I*; and to be able to use the force-pump successfully for this purpose I find it best to submit the current of fumes and gases to a preliminary cooling, in order to somewhat increase their density before they pass through the force-pump. This preliminary cooling or condensation is accomplished by the spray of water thrown from the rose or spraying device *l*.

25 There may be a number of pipes *H H* and a number of force-pumps *I*, with corresponding sets of tanks for condensing, without departing from the spirit of my invention.

It is desirable to use two sets of condensing-tanks with each air-pump and pipe, so that while one set of tanks is settling the other set may be connected with the air-pump and be performing the operation of condensing.

40 It is obvious that the hollow partition may be utilized as a steam-generator, and by proper connections the steam generated could be used for purposes of driving machinery or for heating purposes.

45 Having thus described my invention, what I claim as new, and desire to secure by Letters Patent, is—

1. The combination, with a furnace, of the central flue, *B*, connecting cross-flue *G*, provided with valve *i*, the pipe *H*, and exhaust-pump *I*, all arranged substantially as herein shown and described.

2. The furnace *A*, having a series of draft-openings at its bottom, in combination with the vertical hollow partition *C*, provided with water-pipes *b b'*, the concentrically-arranged perforated air-pipes *E*, pipe *F*, and blower central flue, *B*, connecting cross-flue *G*, having valve *i* and spraying device *l*, pipes *H*, exhaust-pumps *I*, and condensers *K*, substantially as and for the purpose herein shown and described.

55 60 SAMUEL P. SPOONER.
